US00D786733S

(12) United States Design Patent (10) Patent No.: US D786,733 S
(45) Date of Patent: * May 16, 2017

(54) PRECIOUS STONE

(71) Applicant: Amin Luxury S.R.L., Florence (IT)

(72) Inventor: Bobak Moghaddam Nasrollahi,
Florence (IT)

(73) Assignee: Amin Luxury S.R.L., Florence (IT)

() Term: 15 Years

(21) Appl. No.: 29/544,167

(22) Filed: Oct. 30, 2015

(30) Foreign Application Priority Data

Sep. 25, 2015 (EM) 002779751-0001

(51) LOC (10) Cl. 11-01

(52) U.S. Cl.

USPC D11/90

(58) Field of Classification Search

USPC D11/1-2, 26-29, 89-92; 63/26-28, 32

CPC A44C 17/00

See application file for complete search history.
